UNITED STATES PATENT OFFICE.

ROSE DE LIMA MEIER, OF NEW YORK, N. Y.

ADJUSTABLE BED.

Application filed February 1, 1924. Serial No. 689,847.

To all whom it may concern:

Be it known that I, ROSE DE L. MEIER, a citizen of the United States, residing at New York, in the county of New York and

5 State of New York, have invented certain new and useful Improvements in Adjustable Beds, of which the following is a specification.

10 The main object of this invention is to provide a foldable bed which may be collapsed longitudinally in order to take up a relatively smaller amount of space when the bed is not in use.

15 Another object is to provide a foldable bed as mentioned, in which the long sides of the bed frame are divided into a plurality of hinged sections, these sections being drawn toward each other by novel means in order to shorten the frames to take up a 20 smaller amount of floor space.

These and other objects will become apparent in the description below, in which characters of reference refer to like-named parts in the drawing.

25 Referring briefly to the drawing, Figure 1 is a side elevational view of the bed when fully extended for use.

30 Figure 2 is a top plan view of the bed in collapsed position, the bed spring supporting means being omitted from the view for the sake of clarity and to identify the remainder of the structure.

35 Figure 3 is a perspective view of the bed in partially folded position.

Figure 4 is a longitudinal sectional elevational view of the bed frame mover means.

Referring in detail to the drawing, the numerals 1 and 2 indicate the end sections of the bed. These end sections are set up 40 on legs 3 and have boards 4 rigidly secured to their upper ends. The end sections have side boards 5 rigidly attached to the legs and extend inwardly and toward each other. Intermediate boards 6 are connected to the 45 adjacent ends of the boards 5 by hinges 7, these hinges being secured to the mutually adjacent faces of the boards 5 and 6. The free ends of the boards 6 have floating side frames 8 and 8^a secured thereto, the securing

50 means being hinges 9 which are attached to the opposing surfaces of the boards 6 and the floating side frames 8 and 8^a, the latter being supported on legs 10. The mutually adjacent edges of the boards 4 have hinge members 11 secured near their corners. These hinges are connected to spring sup-

port beams 12 and 13. Intermediate the length of the floating side frames 8 and 8^a, openings are provided. In the opening provided in the frame 8^a, a sleeve 14 having a longitudinal slot 15 is anchored. In the opening provided in frame 8, a shaft 16 having its greater length internally threaded, is anchored by a pin 16^a which projects into the opening of the frame 8. An L-shaped bracket 17 having a slot 18 is connected to the lower edge of the floating side frame 8^a by passing the slotted end 17 over the shoulder bolt 19, the latter being rigid on the side frame 8^a. The vertical arm of the bracket is hingedly connected to a plate lever 21, the purpose of which will be more fully described. An opening in member 20, aligned with the internal threaded opening in member 16, receives a winding crank 21^a, the extending end of the crank being of the same length as the width of the bed and being threaded externally thruout its length.

When the bed is used, the same is fully extended, as shown in Figure 1. In this position, the beams 12 and 13 lie horizontally, as indicated in Figure 1. The intervening space between the beams 12 and 13 is provided with a flexible bed spring (not shown), the edges of the spring being secured to the beams in any desirable manner. The spring may then be covered with a mattress 22 and the necessary linen provided for occupancy. It is to be noted that while the bed is being used for sleeping purposes, the bracket 17 and the crank 21 are entirely removed from the floating frames, and the appearance of the bed is as shown in Figure 1. When the bed is to be folded, the bracket 17 is lifted so that the slot 18 is inserted over the shoulder bolt 19 in such position that member 20 of the bracket extends vertically upward. The lever 21 is urged toward the side frame 8^a so that its free edge is pried under the intersecting ends of the beams 12 and 13, supported on the floating side frame 8^a. The threaded end of the crank 21 is then inserted into the threaded opening of member 16 and said crank rotated. As rotation continues, the bracket 17 slides toward the floating side frame 8^a and as the member 21 is in angular position, the intersecting ends of the beams 12 and 13 are slightly lifted at their point of intersection. Continued rotation of the crank causes the bracket 17 to move to the limit of the slot

18 and when said bracket is then firmly anchored in stationary position, member 16 will be drawn toward the bracket. As the latter is secured to the floating side frame 5 8, said side frames 8 and 8^a will be drawn mutually toward each other, the limit of this movement being when the boards 6 are at right angles to the side frames. As this position of the bed is arrived at, the bracket 10 17 is removed and the crank 21^a withdrawn from shaft 16. By urging the end sections 1 and 2 toward each other, the entire bed may be collapsed to the position shown in Figure 2 in which the members 5, 6, 8, and 15 8^a are illustrated parallel to their adjacent members. In this manner, the length of the bed is reduced to one third of its original length, and consequently requires only one third of the amount of floor space. Beams 20 12 and 13 extend angularly upward when the bed is in collapsed position, and the mattress 22 is in a better position to receive an airing.

I claim:—

25 1. A folding bed comprising a pair of end sections having legs supporting the same, intermediate floating side frames having legs supporting the same, boards hingedly connected to said floating frames, the opposite ends of said boards being connected to the end sections, a slotted sleeve connected to one floating frame, a shaft having one end secured to the opposite floating frame, said shaft being slidable in the 30 35 slotted sleeve the securing means passing thru the slot of the sleeve, a bracket, a

crank supported in said bracket and engaging the shaft, said crank when rotated being adapted to move the floating frames mutually toward each other, spring support 40 beams hingedly connected to the end sections, and means for lifting the intersecting ends of said beams upwardly when rotating said crank.

2. A folding bed comprising a pair of end sections having legs supporting the same, intermediate floating side frames having legs supporting the same, boards hingedly connected to said floating frames, the opposite ends of said boards being connected to the end sections, a slotted sleeve connected to one floating frame, a shaft having one end secured to the opposite floating frame and being adapted to slide in the slotted sleeve, the securing means passing thru the slot of the sleeve, a bracket, a crank supported in said bracket and engaging the shaft, said crank when rotated being adapted to move the floating frames mutually toward each other, spring support 45 beams hingedly connected to the end sections, 50 the bracket being slotted, the shoulder bolt supporting the slotted end of said bracket beneath the side frame carrying the sleeve, a hinged lever plate connected to said bracket, said crank when rotated being adapted to urge the bracket inwardly to the limit of the slot, the plate lever causing the spring supporting beams to be lifted 55 angularly upward.

In testimony whereof I affix my signature.

ROSE DE LIMA MEIER.
